UNITED STATES PATENT OFFICE.

GERRIT HILGERS, OF ROTTERDAM, NETHERLANDS.

LOCKING AND RELEASING DEVICE FOR BOAT-TACKLES.

1,331,432.

Specification of Letters Patent. Patented Feb. 17, 1920.

Application filed January 6, 1919. Serial No. 269,881.

To all whom it may concern:

Be it known that I, GERRIT HILGERS, a subject of the Queen of the Netherlands, residing at Rotterdam, Province of South Holland, in the Kingdom of the Netherlands, have invented certain new and useful Improvements in or Relating to Locking and Releasing Devices for Boat-Tackles, of which the following is a specification.

10 This invention relates to locking and releasing devices for boat-tackles.

It is important, that boats, while being lowered are released from the falls exactly at the right moment and it is desirable, that 15 not only this releasing takes place at the exact moment, but that both falls, by means of which the boat is suspended are released simultaneously.

According to the invention both tackles 20 are loosened simultaneously by a single manipulation. The choice of the exact moment must of course be left to the operator of the device, consequently to one man only.

According to the invention the arrangement 25 consists of two locking-bolts, rotary mounted on fixed trunnions from which bolts the boat is suspended by means of the falls. The bolts abut with a beveled edge in such a way against the also beveled faces 30 of the closing-rods which are rotary mounted on two-fixed trunnions and connected with each other by means of a coupling rod, that the closing members have a tendency to swing and to release the locking device under the influence of the strain on the bolts.

One of the closing rods is provided with 35 an extension provided with a handle, which in the locking-position of the bolts can be fastened.

40 The invention is hereinafter described with reference to the accompanying drawings.

Figure 1 shows a longitudinal section of a boat with my locking and releasing device; 45 and Fig. 2 shows the mechanism of the device on a larger scale.

The tackle-blocks engage the horizontal locking-bolts 3 and 4 by means of a hook or eye 1 and 2. The locking-bolts are rotary 50 mounted on the trunnions 5 and 6, fixed to the stationary bolts 7 and 8 or the like secured to the bottom of the boat "A." The locking-bolts 3 and 4 are beveled at their front ends so as to form an inclined face 55 9, 10.

The bolts being locked, these inclined faces

abut with the also inclined faces of the closing-rods 11 and 12, which are rotatably mounted on the fixed trunnions 13 and 14 secured to the bottom of the boat. The closing-rods 11 and 12 are connected by means of a connecting rod 15, pivoted to the said closing-rods 11 and 12.

The weight of the boat and crew suspending from the bolts 3 and 4, will tend to 60 swing the rods 11 and 12 about the trunnions 13 and 14, under the influence of the beveled faces, 9 and 10; in the drawing the rods 11 and 12 tend to swing to the left. One of the rods is provided with an extension 65 carrying a handle, which can be fastened in some suitable manner f. i. by means of a pin or in the way of the brake-levers of motor-cars.

The device can be rapidly applied to a 70 boat and occupies but little space when applied, the handle 16 only extending sufficiently high to be easily operated.

As in these arrangements the operation of the handle does not require any exertion of 75 power, but on the contrary the said handle always has a tendency to move, the pulling over of the handle on the precise moment and therefore the releasing of the falls is always guaranteed.

By regulating the inclination of the faces 9 and 10 and placing the beveled edge of the closing-rods more or less close to the trunnions 13 and 14, the pressure exerted on the said rods can be regulated.

What I claim is:

1. A locking and releasing device for boats, comprising two pivoted locking bolts with which the falls suspending the boat are adapted to engage, said bolts having their free ends beveled, two pivoted closing rods having beveled faces with which the beveled ends of the locking bolts engage, one of the rods being extended to form a handle, and a rod connecting the closing rods. 100

2. A locking and releasing device for boats, comprising two pivoted bolts with which the falls suspending a boat are adapted to engage, two pivoted members, one forming a handle and with each of 105 which the free end of a bolt has locking engagement, and a link connection between the said members.

In testimony whereof I have hereunto set my hand.

GERRIT HILGERS.
